CONVERSION OF HYDROCARBONS

Crawford H. Greenewalt, Wilmington, Del., assignor to E. I. du Pont de Nemours & Company, Wilmington, Del., a corporation of Delaware

Application December 30, 1937, Serial No. 182,410

1 Claim. (Cl. 260—668)

This invention relates to the manufacture of low molecular weight olefins and aromatics from petroleum, and more particularly, pertains to the production of normally gaseous olefins such as ethylene and normally liquid aromatics such as benzene, toluene, and xylenes.

The fundamental principles applied by petroleum refiners in producing gasoline and related products from hydrocarbon oils by pyrolysis at elevated temperatures have been known for a long time. It is also well known that most processes which have previously been proposed for making olefins and aromatics by oil cracking, convert relatively small proportions of the oil to olefins or aromatics and yield the latter in a very impure state. It is well known that the effectiveness of many of these processes is based on cracking conditions which are so severe that sustained continuous operation is impossible because of failure of materials of construction or due to blocking of vital equipment parts with carbon. This invention constitutes an improvement over existing methods.

One object of this invention is to provide an effective method for obtaining high yields of olefins, especially ethylene and/or propylene, from petroleum oil. Another object is the simultaneous conversion of an appreciable portion of the oil to aromatic compounds and especially to benzene, toluene, and xylenes. A further object is the production of these aromatic compounds in a relatively pure state and in relatively high yields, from which undesirable contaminants can be readily removed. A still further object is the achievement of the above ends under such conditions that continuous operation is possible for long periods of time. Other objects will appear hereinafter.

The above mentioned objects are accomplished by the following invention which comprises the cracking of hydrocarbons such as an oil vapor, under conditions that produce lower olefins and aromatic hydrocarbons, separating the products of cracking or these products admixed with those of a separately operated gas cracking process into various fractions including a gaseous fraction predominating in hydrocarbons within the range of C₂ to C₄, inclusive, and cracking at least a portion of this fraction under conditions that produce olefins and aromatic hydrocarbons.

This invention will be more thoroughly understood by referring to the following specification and to the accompanying drawing in which the preferred arrangement of apparatus for carrying out the invention is illustrated diagrammatically. It is to be understood that details of this equipment which are familiar to those skilled in the art have been omitted for the sake of clarity, that modification in constructional details and

in arrangements of parts may be made without departing from the spirit of this invention, and that such factors should not be limitations except as may be required by the claim.

Referring more particularly to the drawing, raw material which may, for example, be "gas-oil" or other petroleum oil, is delivered from a suitable storage through line 1 to pump 1A by means of which it is transferred via pipe line 2 to work tank 3. The fresh, raw material is mixed in work tank 3 with other oil fractions which will be subsequently described. The mixture leaves tank 3 through line 4 and is delivered by pump 5 through line 6 to preheating coil 7. This and other coils are suitably arranged in banks in a furnace setting. The preheating bank is preferably heated by the waste gases discharged from a combustion chamber of the furnace in order that the gases vented to the stack will be at a minimum temperature. The charging stock is forced serially through the tubes of preheating bank 7 in order that the oil may be heated to a vaporizing temperature of approximately 325° to 385° C. Ordinarily little thermal decomposition of the oil takes place in preheating coil 7.

The material discharged from preheating bank 7 passes by way of pipe line 8 to an evaporator 9 wherein the high boiling constituents, which have remained in a liquid state at the preheater 30 exit temperature, are dropped to the base of the evaporator and withdrawn through outlet 9A and passed, first through cooler 10, and then by means of pipe line 11 to suitable storage tanks. The lighter oils which are in a vaporized state 35 in evaporator 9, pass overhead from the latter through outlet line 12 and are introduced into drying bank 13 which is situated in an intermediate temperature zone in the furnace setting, and like preheating coil 7, is largely heated by waste products of combustion.

The oil passes serially through the tubes which comprise the drying bank and its temperature is raised to about 460° to 490° C. The temperature-time relationship in this bank is so adjusted 45 that extensive cracking does not occur. Owing to inefficient separation of mist and vapor in the evaporator and to condensation in transfer line 12, a small amount of liquid oil is sometimes charged to the drying coils. This liquid, however, 50 is effectively evaporated in the drying bank, which discharges a substantially dry vapor.

After being thoroughly dried in coil 13, the hot vapors are introduced into a bank of cracking or conversion tubes 14. These tubes are arranged serially in the radiant section of the furnace setting, preferably around the sides and top wall of the main combustion chamber. It is desirable to raise the temperature of the vapors leaving the drying zone as rapidly as possible to the active conversion temperature i. e. above about 650° and

preferably about 690° to about 710° C. The vapors are maintained at this high temperature level in the latter portion or soaking section of bank 14. It will of course be realized that at this high reaction temperature, precautions must be taken to avoid the deposition of carbon in the reaction tubes and to prevent injuries to them. These difficulties are avoided by careful location of the tubes with respect to the furnace setting and burner flames, and by maintaining high velocities of oil vapor through the tubes in order that the heat applied to them may be promptly absorbed and carried away.

The hot reaction products, which have been held at a substantially constant temperature in the soaking section of 14, are discharged through pipe 15 into arrester 16. The arrester is simply a chamber into which a cold, relatively volatile hydrocarbon fraction is introduced through a suitable spray nozzle. The hot reaction products and the cold spray are intimately mixed, the latter is largely evaporated, and the temperature of the reaction products is dropped almost instantaneously from about 700° to about 250° C. This quenching procedure terminates the cracking reaction abruptly. The mixture of quenched reaction products and vaporized quenching medium leaves arrester 16 by means of line 17 and is there joined by a similar mixture which enters line 17 by way of line 51. The material in line 51 consists of reaction products and quenching stock from a gas cracking operation which will be described in detail later. The above composite then passes into the base of tower 18. The function of this tower is to separate the high boiling constituents formed during the cracking reaction, from unconverted charge and lower boiling materials. The heavy oils and tarry materials, which may find use as fuel oils, are discharged from the base of the tower 18 through outlet 19 and cooler 20 and are finally sent to storage vessels through pipe line 21. The vapors which separate from the hot liquid at the base of tower 18 are scrubbed in the upper portion of the tower by descending, relatively volatile oil which has been introduced into the top of the column as reflux through line 29. The terminal temperature conditions of tower 18 are adjusted by varying the rates of quench liquid to arrester 16 and of reflux to the tower so that the vapors emerging from the top of the column to line 22 are free from heavy, tarry constituents and that the fuel oil fraction discharge at the base is substantially free from volatile constituents which might have further value as cracking stock.

The vapors issuing from the top of tower 18 pass by means of line 22 to the base of tower 23. Its purpose is to separate unconverted raw material or constituents in essentially the same boiling range from lower boiling liquids and fixed gas. The gas and vapors pass up through and are scrubbed by the liquid on the trays of the fractionating tower. A light distillate having an end point of perhaps 150° to 200° C. is pumped into the top of tower 23 through line 38 to serve as reflux. Sufficient reflux is added in this manner so that the vapors, if cooled to condense constituents boiling in the gasoline range, give a condensate which has an end point of about 190° C. The higher boiling materials descend to the base of the fractionating tower where they are discharged by means of outlet line 24 through cooler 25. A portion of the cooled bottoms from the fractionating tower 23 passes to pump 75

through line 27 and is introduced by way of line 29 into the top of tower 18 to serve as reflux there. The remainder returns by means of lines 26 and 2 to work tank 3 where it is mixed with fresh charge and the steps outlined above repeated to effect further cracking.

The effluent vapors leave tower 23 through outlet 30, pass into condenser 31, and are there cooled to about 30° C. The pressure at this point 10 is about 10 lbs. per sq. in. gage. Under these conditions an appreciable amount of liquid is formed in the condenser and passes together with 15 uncondensed vapors to a gas-liquid separator 33 by means of line 32. Light distillate is withdrawn from the base of this separator through outlet 34. A portion is delivered through line 35 to pump 36 which forces the material through line 37 and thence through lines 37A and 38 to 20 furnish quenching medium and reflux to the arrester 16 and fractionating tower 23, respectively. The light distillate made above that used for 25 quenching and refluxing is withdrawn from the system to suitable storage tanks through line 34. This distillate is aromatic in character and may contain an aggregate of better than 50% benzene, toluene, and xylenes.

A complex gas mixture containing hydrogen, 30 methane, ethylene, ethane, propylene, propane, butylenes, and higher boiling hydrocarbons is withdrawn from the top of separator 33 through line 39, and passed into recovery plant 40. Here the mixture is separated into the following fractions: (1) hydrogen and methane, (2) ethylene, (3) a mixture of ethane, C₃ and C₄ hydrocarbons, 35 and (4) higher boiling hydrocarbons.

The hydrogen and methane fraction which 40 may serve as fuel is discharged from the recovery plant through line 42. Ethylene is released via line 43 to suitable storage or directly to processes in which it may be used as raw material.

The fraction comprising ethane and C₃ and C₄ hydrocarbons is delivered to pump 44 by means 45 of which it is forced through pipe line 45 and thence into the preheating coil 46. This and other gas treating coils are arranged in a furnace setting designed for high temperature service and the preheating coil is preferably situated so that it is heated largely by waste combustion 50 gases. Such portion of the charge as may be in a liquid state under inlet temperature and pressure conditions is completely vaporized as it passes through the tubes of preheating bank 46 in which a final temperature of 650° to 700° C. 55 is attained. The hot gases are then introduced into a bank of cracking or conversion coils 47, which coils are maintained at a temperature of about 760° to about 790° C. These coils are preferably situated in a radiant section of the furnace setting. The time-temperature relationship in 60 coils 47 is so regulated that about 50% of the incoming ethane, C₃ and C₄ hydrocarbons are converted to other compounds; for example, hydrogen, methane, ethane, ethylene, and hydrocarbons in the motor spirit boiling range. The 65 50% conversion means the average of ethane, C₃ and C₄ conversion, and not a 50% conversion of each constituent. High vapor velocities are employed in the conversion tubes to prevent excessive tube wall temperatures and to minimize carbon deposition.

The hot reaction products are discharged from the conversion zone 47 through line 48 into arrester 49. Arresters 49 and 16 may be similar in design. The products of gas cracking are re-

duced instantly from reaction temperature to about 120° C. by quenching with a volatile fraction which is withdrawn from line 37 through line 50 to the arrester spray nozzle. The mixture of quenched reaction products and quenching stock leaves arrester 49 by means of exit line 51 and joins a similar mixture discharged from oil cracking arrester 16. The combined quenched products from oil cracking and gas cracking pass through the base of the flash tower 18 via line 17. From this point on, the equipment for processing the reaction products is common to both cracking stages and, with the exception of recovery plant 40, functions in the manner previously described. It should of course be realized that the invention is not limited to the use of the same equipment for the separation of the products in each of the cracking steps. Separate equipment may, of course, be used.

The constituents comprising the higher boiling hydrocarbon fraction, which is separated in recovery plant 40, are now obtained from the gas fractions produced by oil and gas cracking operations. This higher boiling mixture is discharged from recovery plant 40 through line 41 and may be mixed with the liquid from the gas and liquid separator 33 by introducing same into line 34 or the higher boiling fraction may be recovered as a separate fraction via line 52. By this combination of oil cracking and gas cracking, it has been found that there is a marked increase in yields of gaseous products from hydrogen to C₃ hydrocarbons, inclusive, and of benzene, toluene, and xylenes over a process in which merely the oil cracking step is carried out.

The following example is a specific illustration of the invention described herein:

Example

A hydrocarbon distillate with characteristics similar to those of the petroleum fraction known to refiners as "gas oil" was used as a raw material in the process outlined above. This material was mixed in a work tank with partially cracked and unconverted material in the ratio of 58.1 parts by weight of fresh charge to 41.9 parts of recycle stock. The manner in which this recycle fraction was obtained will be described in detail later.

The above mixture was pumped at the rate of 410 pounds per hour through a bank of pre-heating or vaporizing tubes arranged in series. These tubes were so mounted in a furnace setting as to be heated largely by waste gases passing from the main combustion chamber of the furnace to its stack. The oil mixture was heated to 348° C. in the preheating section and was discharged at this temperature into the lower part of an evaporator. This was a vertically mounted steel vessel with a section above the oil-inlet filled with packing rings. Eighty-five pounds per hour of steam were also admitted to the evaporator. The high boiling constituents of the hot oil mixture dropped to the base of the evaporator and were withdrawn and cooled at the rate of 37.3 pounds per hour. Since the constituents of the recycle stock were relatively low boiling, the evaporator bottoms were mostly uncracked, high boiling ends from the fresh charge. The vaporized oil and steam passed overhead through the bed of packing, left the evaporator at 285° C., and then passed through the tubes of a drying coil in which the temperature of the vapor was raised to 496° C. After leaving the drying coil, the vapors were trans-

mitted to a bank of cracking or conversion tubes which were arranged in series around the top wall of the main combustion chamber. The temperature of the vapors was raised rapidly to 695° C. in the cracking zone and was maintained at substantially this temperature in a soaking coil which was also situated in the radiant section of the furnace.

The hot reaction products from the soaking zone were discharged to an arrester chamber and there intimately mixed with a cold spray of about 500 pounds per hour of a light, distilled hydrocarbon fraction. This procedure gave a temperature of about 270° C. at the arrester exit, from which the mixture of quenched reaction products and vaporized quenching stock was passed to the base of a fractionating tower. The quenched products from a second, or gas cracking furnace, to be described later, were also received by the same tower. The heavy, tarry products of oil and gas cracking accumulated at the bottom of this tower, and 54.4 pounds per hour, suitable for fuel oil, were withdrawn and cooled. The lower boiling materials, including gas, steam, constituents in the gasoline boiling range, and unconverted and partially cracked charging stock, were taken off overhead as vapor and passed into the base of a second fractionating column. Gas, light distillate, and steam were distilled from the top of the second tower while higher boiling materials were discharged from its base and cooled. Five hundred and thirty pounds per hour of these cooled bottoms were pumped into the top of the first fractionating tower to serve as reflux there. The remainder was mixed with incoming fresh feed oil in the proportions indicated earlier, and recharged to the preheating zone of the oil cracking furnace. The overhead vapor from the second fractionator was cooled in a condenser and the resulting mixture of vapor and condensate was discharged to a gas-liquid separating chamber. The two towers and the separator were operated at a pressure of 8 to 10 pounds per sq. inch gage. Water, condensed from steam admitted earlier in the process, was released from the base of the separator. Light distillate was pumped from this separator to the top of the second tower as reflux as well as to the arrester of the oil cracking unit described above, and also to that of a gas cracking unit to be described below. The excess of distillate was withdrawn from the separator and passed to a storage tank.

Gaseous products of oil and gas cracking, amounting to 3080 cu.ft./hr. (on water free basis at 0° C. and 1 atm. pressure) were vented from the top of the gas-liquid separator and conveyed to a gas recovery plant. The crude gas had approximately the following composition.

	Mol. per cent
H ₂	8.7
CH ₄	17.6
C ₂ H ₄	21.4
C ₂ H ₆	16.4
C ₃	22.3
C ₄	7.3
C ₅ and higher	6.3
	100.0

The gas was separated in the recovery plant into the following fractions: (1) hydrogen and methane, (2) ethylene, (3) a mixture of ethane, C₃, and C₄ hydrocarbons, and (4) a light aromatic distillate containing C₅ and higher hydro-

carbons. Fraction 3 was vaporized and forced together with 28 pounds per hour of steam into a bank of preheating tubes in a separate gas cracking furnace. The mixture of steam and hydrocarbon vapor was heated to 690° C. in the preheating zone and was then passed serially through the tubes of a cracking or conversion coil in which the vapors reached a temperature of 750-760° C. As in the case of the oil cracking furnace, the preheating coil was heated largely by convection and the conversion coil chiefly by radiation. Approximately 50% of the aggregate charge was converted to products other than C₂H₆, C₃, and C₄ hydrocarbons in a single passage through the gas cracking furnace. The temperature of the hot cracked products was dropped almost instantaneously to 135° C. by quenching with cold distillate pumped from the gas-liquid separator into an arrestor at the exit of the gas cracking coil. The quenched products joined a similar mixture from the oil cracking operation and both were fractionated into gas, light aromatic distillate, recycle stock, and refractory fuel oil in a common separation system. Fraction 4 above from the recovery plant, and the excess of condensate withdrawn from the gas-liquid separator following the cracking units' fractionating towers, amounted to 59.6 pounds per hour. This light distillate was very aromatic in character and contained much benzene, toluene, and xylene.

It has been previously mentioned that the bottoms obtained from the evaporator used in the oil cracking operation were substantially unvaporized fresh feed oil. The following yields were obtained based on 100 parts by weight of vaporized fresh feed.

H ₂ -----	*0.7
CH ₄ -----	*12.1
C ₂ H ₄ -----	*25.6
Aromatic distillate -----	30.0
Refractory fuel oil -----	27.4
 Total -----	95.8

*Prior to losses in gas recovery plant.

It should be understood that the successful application of this invention is not limited to the use of a single raw material. The use of gas oil has been mentioned but other stocks such as crude petroleum and topped or reduced crude may also be employed. A "viscosity breaking" operation may be used to advantage in conjunction with the oil cracking step if the raw material has a high pour point and high viscosity.

Steam may be used to adjust the contact time in the cracking sections of the oil and gas furnaces mentioned. The process, however, will function adequately without steam and its use is optional.

The invention pertains to improving the yield of olefins and aromatic hydrocarbons being applicable to any cracking process where these products are obtained. In the cracking of hydrocarbons at temperatures in excess of 600° C. olefins and aromatic hydrocarbons are produced in substantial quantities, this invention is particularly applicable in such instances. The upper temperature limit of the cracking reactions in which olefins and aromatic hydrocarbons are produced depends upon the length of time the hydrocarbons to be cracked remain under the cracking conditions. The shorter the time of cracking the higher the temperature that can be

used, thus temperatures of about 900° C. have been used and it is possible to use even higher temperatures if the length of time of cracking is properly adjusted. The oil cracking may be carried out in the tubular type cracking units as disclosed herein at 600° to 750° C. but it is preferred to operate at 690-710° C. and to adjust the time-temperature relationship so that 40 to 60% of the total vaporized oil charge is cracked in a single passage through the cracking zone. It is also desirable to operate the gas cracking step in such a way that a per pass conversion of the same order of magnitude is achieved. In the tubular type cracking unit it is preferable to operate the gas cracking step at higher temperatures than the oil cracking step, usually at least 50° C. higher. It is possible that the gas cracking step could be carried out at a temperature the same as or lower than the oil cracking step provided that the length of time of cracking in the gas cracking step is properly adjusted to produce olefins and aromatic hydrocarbons.

It is desirable to maintain high vapor velocities in the high temperature zones to avoid overheating of cracking tubes and deposition of coke. It is also important from the standpoint of continuity of operation to effect an efficient separation between cracked tar and lower boiling materials. The necessity of avoiding carbonaceous material in recycle stocks is familiar to those versed in the cracking art.

The production of ethylene has been emphasized but other hydrocarbons, such as the lower olefins, can also be readily produced. For example any or all of the propylene in the raw gas may be separated in the gas recovery plant and withdrawn from the process. In this case, the C₂H₆ and C₄ hydrocarbons, with or without the propylene originally present, would serve as charging stock for the separately operated gas cracking operation. The process is equally flexible as regards the production of ethane or C₄ hydrocarbons. The production of an aromatic distillate rich in benzene, toluene, and xylenes has been particularly mentioned but higher aromatics, including naphthalene, may be obtained by operating the fractionation equipment so that distillate of a higher end point is produced.

The invention is not limited to the particular point of separation which is made between the higher molecular weight fraction and the lower molecular weight gaseous fraction which is cracked in the separate cracking step. The charging stock for the latter may contain a small amount of C₅ constituents or may be relatively free from constituents higher in molecular weight than C₄.

The choice of the various conditions must depend on such factors as the nature of the primary raw material, the operating conditions maintained in the two cracking steps, and the relative quantities of the several products desired.

A very important advantage of this invention is that high yields of gaseous olefins and of aromatics are obtained under such conditions that continuous operation is possible for long periods of time. Overheating and burning out of cracking tubes and excessive production of hydrogen and methane is avoided.

It is apparent that many widely different embodiments of this invention may be made without departing from the spirit and scope thereof and therefore it is not intended to be limited except as indicated in the appended claim.

I claim:

The process for the production of ethylene and aromatic hydrocarbons which comprises cracking a normally liquid hydrocarbon oil vapor derived from petroleum oil by passing said vapors through a cracking zone heated to a temperature between 650° and 750° C., said passage being at such a rate that 40 to 60% of the vapors undergoes the cracking reaction, immediately reducing the temperature of the hot gases from the 10 cracking zone to one not above 270° C. by quenching same with a cold spray of hydrocarbon distillate, separating the resulting cracked products into the following fractions—a fraction containing hydrogen and methane, a second 15 fraction containing product olefins, a third fraction containing an aromatic distillate, and a fourth fraction comprising essentially ethane and C₃ and C₄ hydrocarbons freed of the desired

products; cracking the fourth fraction by passing same through a second cracking zone operated at a temperature at least 50° higher than the temperature of the first cracking zone but at a temperature not exceeding 800° C., said passage being at such a rate that 40 to 60% of the gas undergoes the cracking reaction, immediately reducing the temperature of the gas from the cracking zone to a temperature of about 120° C. to about 135° C. by quenching same with a cold spray of a hydrocarbon distillate in a quenching step separate from the quenching step following the first cracking step, and combining the cracked quenched products of the second cracking step with those of the first cracking step, this process being further characterized in that it is carried out at a pressure of about one atmosphere..

CRAWFORD H. GREENEWAHLT.
